[57] CLAIM

The ornamental design for a front control panel for a
combined automotive radio and cassette player, as
shown and described.

DESCRIPTION

FIG. 1 is a front, top, and right side perspective view of
a front control panel for a combined automotive radio
and cassette player showing our new design;

FIG. 2 is a left side elevational view thereof;

FIG. 3 is a right side elevational view thereof;

FIG. 4 is a top plan view thereof;

FIG. 5 is a front elevational view thereof; and,

FIG. 6 is a bottom plan view thereof.

The broken line showing of the combined radio and
cassette casing is for illustrative purposes only and
forms no part of the claimed design.
